DISPLAY, DISPENSING AND STORAGE CABINET

Harvey J. Smith, Greensboro, N.C., assignor to Modern Metal Products Company, Greensboro, N.C.

Filed Sept. 17, 1971, Ser. No. 181,646

Term of patent 14 years

Int. Cl. D6—04

U.S. Cl. D6—170

FIG. 1

FIG. 3

FIG. 4

FIG. 2

FIG. 5

FIG. 1 is a perspective view of the cabinet with the doors closed illustrating the front and left sides thereof;

FIG. 2 is a right side elevational view of the cabinet of FIG. 1;

FIG. 3 is a top plan view of the cabinet;

FIG. 4 is a rear elevational view of the cabinet; and

FIG. 5 is an enlarged perspective view of the cabinet similar to FIG. 1 with the doors in opened positions.

I claim:

The ornamental design for a display, dispensing and storage cabinet, as shown and described.
